UNITED STATES PATENT OFFICE.

EUGENE I. ROSENFELD, OF BALTIMORE, MARYLAND.

DESIGN FOR A GARMENT-SUPPORTER.

SPECIFICATION forming part of Design No. 30,919, dated May 30, 1899.

Application filed May 2, 1899. Serial No. 715,375. Term of patent 3½ years.

To all whom it may concern:

Be it known that I, EUGENE I. ROSENFELD, a citizen of the United States, residing at Baltimore, in the State of Maryland, have invented and produced a new and original Design for a Garment-Supporter; and I do hereby declare the following to be a full, clear, and exact description of the invention, such as will enable others skilled in the art to which it appertains to make and use the same.

This invention is a design for garment supporters or clips; and it consists of oppositely-disposed spaced loops having their open ends facing, opposite members joined by a connection of zigzag form, and short arms projecting outward in opposite directions from the other members of the loops, all the parts being in the same plane.

The design, as shown in the drawing, consists of loops 1, located a distance apart and in line, with their open ends facing. A con-

nexion of zigzag form joins opposite members of the loops and consists of short arms 2, arranged at an obtuse angle to their respective loops, and a diagonal bar 3. Short arms 4 project from the other members of the loops in an opposite direction to the arms 2 and terminate in eyes 5. The arms 2 and 4 recede from the loops on divergent lines. The loops 1 have a longitudinal disposition 30 and aline and all the parts are in the same plane.

Having thus described the invention, what is claimed as new is—

The design for a garment-supporter, substantially as herein shown and described.

In testimony whereof I affix my signature in presence of two witnesses.

EUGENE I. ROSENFELD. [L. S.]
